PUMP

Campling William Meader, Burntisland, Scotland

Application April 10, 1950, Serial No. 154,921

Claims priority, application Great Britain
May 6, 1949

6 Claims. (Cl. 103—50)

1

The invention relates to pumps which are particularly though not exclusively intended for pumping thick semi-liquid substances, such as mud, bauxite residues, paper pulps, sewage, sleech, cement slurries, unset concrete, oil residues, filter cake, sludges, clays, silt, pastes, material prepared for the making of bricks, and all materials which are in a plastic state at normal pressures and temperatures. Such thick semi-liquid substances are hereinafter referred to as "mud." The object of the invention is to provide a pump which shall be capable of pumping muds of various moisture contents, ranging from mud in a more or less fluid state to mud in a stiff plastic state.

Forms of pump according to the invention will now be described by way of example, and with reference to the accompanying drawing wherein:

Fig. 1 is a side elevation in section of a pump according to the invention,

Fig. 2 shows the pump in a position subsequent to the cutting movement of the first cylinder,

Fig. 3 shows a pump in a position subsequent to the pumping movement of the first piston,

Fig. 4 is an end elevation of the pump shown in Fig. 1 on the line IV—IV, and

Fig. 5 is a broken side elevation in section of an alternative form of pump.

Supported on a frame 1 is a chamber 2 of part-cylindrical shape for receiving from a hopper 3 the mud which is to be pumped. One end wall 4 of the chamber 2 has an aperture 5 and a tapered pipe 6 extends from said aperture. The end of the tapered pipe 6 is connected to a discharge pipe 7 through a diagrammatically indicated automatic non-return valve 8. Around the aperture 5 on the inside wall is an annular seating 9 for the open end 10 of an axially movable cylinder 11. At the other end of the chamber 2 and arranged coaxial therewith and coaxial with the aperture 5 is a second and fixed cylinder 12 which extends outwards from the chamber. The movable open-ended cylinder 11 is supported in a bearing 13 at the front end of the fixed cylinder 12 the said bearing being arranged in an aperture in the other end wall 14 of the chamber. The cylinder 11 is slideable from a position within the fixed cylinder as shown in Fig. 1, to a position in which its open end 10 engages the annular seating 9 around the aperture 5, as shown in Figs. 2 and 3.

Within the movable cylinder 11 is a first piston 15. The movable cylinder 11 is carried on a second piston 16 movable in the fixed cylinder 12.

2

A piston rod 17 for the first piston 15 extends through a bearing 18 in the second piston 16 and is secured to a third piston 19 also movable in the fixed cylinder 12.

5 The second and third pistons are spaced apart in their closest position by a spacer 20 fixed to the piston 19.

The space 21 between the second and third pistons, in the position when the movable cylinder

10 11 and first piston 15 are fully withdrawn from the annular seating 9 as shown in Fig. 1, communicates through a connection 22 with a valve-controlled supply of operating fluid. The space 23 between the second piston 16 and the fixed

15 bearing 13 for the movable cylinder communicates through a connection 24 with a valve-controlled inlet and exhaust for operating fluid. The space 25 between the second and third pistons in the position in which the end 10 of the movable cylinder 11 contacts the seating 9

20 communicates through a connection 26 with a valve-controlled exhaust for the operating fluid, as shown in Fig. 3. The space 27 behind the third piston 19 communicates through a connection 28 in the closed end 29 of the cylinder 12 with a valve-controlled inlet and exhaust for

25 operating fluid.

In operation, the movable cylinder 11 and its piston 15 are withdrawn within the fixed cylinder 12 as shown in Fig. 1. Mud is fed from the hopper 3 to the chamber 2. Operating fluid is supplied through the connection 22 to the space 21 between the second and third pistons, whereby the second piston 16 is moved forwards and the movable cylinder 11, secured thereto is moved into the chamber 2 until its open end 10 engages the annular seating 9, as shown in Fig. 2. By this movement the cylinder 11 becomes filled with mud.

40 The supply of operating fluid is then cut off and operating fluid is supplied through the connection 28 to the space 27 behind the third piston 19 and the space 25 between the second and third pistons is placed in communication with exhaust through the connection 26. The third piston 19 is moved forward driving with it the first piston 15 within the movable cylinder 11. The first piston 15 rams the mud through the aperture 5 and tapered pipe 6 into the discharge pipe 7 for the mud via the automatic non-return valve 8.

When the third piston 19 has reached its extreme position as shown in Fig. 3, the supply of operating fluid to the space 27 is cut off and the space 27 behind the third piston is placed in com-

munication with exhaust while the space 23 between the second piston 16 and the fixed bearing 13 for the movable cylinder is supplied with operating fluid through the connection 24. The second and third pistons are then moved together, carrying with them the movable cylinder and the first piston, to their extreme position within the fixed cylinder as shown in Fig. 1.

More mud falls into the chamber in front of the movable cylinder and the cycle of operations is repeated. When the hopper is full of mud, the chamber 2 is sealed from the atmosphere, so that when the moving cylinder is withdrawn from the aperture after discharge of its load, a partial vacuum is formed, and the contents of the hopper are sucked downwards into the chamber ready to be cut into by the moving cylinder during its succeeding forward movement.

In effect, the invention provides a pump with an inlet valve of maximum cross-sectional area. The bottom of the tapered portion of the inlet to the chamber may be considered as the inlet valve to the pump, and as its area is equal to the projected area of the effective portion of the cylinder, the area of the inlet valve is therefore, a maximum. The cycle of operations can be controlled from a single rotatable valve as will be understood by those skilled in the art.

In the alternative form of pump, illustrated in Fig. 5, the arrangement is similar to that of the pump shown in Figs. 1, 2, 3, and 4. The third piston 19 is, however, supported on a tail rod 30 which is an extension of the piston rod 17, and passes through an aperture 31 in the closed end 29 of the cylinder, to be carried in a tail rod bearing 32. The free end 33 of the tail rod 30 is provided with a cam 34, or push plate which may be used to actuate valves, switches or the like used in the control of the pump.

What I claim is:

1. A pump for pumping mud, comprising a chamber for the mud, said chamber having a wall with a discharge aperture formed therein, a movable open ended cylinder of a length at least as great as that of the chamber axially movable through said chamber, a fixed cylinder adjacent said chamber and secured thereto, a fixed annular seating disposed in said wall surrounding said discharge aperture, a piston axially movable within said movable cylinder, fluid pressure operated driving means to move said movable cylinder axially from a position in which the open end of the movable cylinder is adjacent one end of said chamber to a position in which said open end engages said seating, said driving means including a fluid inlet and outlet formed in said fixed cylinder, and additional driving means to move said piston axially within said movable cylinder.

2. A pump for pumping mud, comprising a chamber for the mud having an open inlet and end walls, said chamber having an opening formed in one of said end walls and a discharge aperture formed in the other of said end walls, an axially movable open ended cylinder of a length at least as great as that of the chamber between the end walls thereof carried slidably in said opening, a fixed cylinder adjacent said chamber and secured thereto, a fixed annular seating for the open end of the cylinder surrounding said discharge aperture, a piston axially movable within said movable cylinder, fluid pressure operated driving means to move said movable cylinder axially from a position in which the open end of the cylinder is adjacent one end wall of

the chamber to a position in which said open end engages said seating, said driving means including a fluid inlet and outlet formed in said fixed cylinder, and additional driving means to move said piston axially within said movable cylinder.

3. A pump for pumping mud, comprising a chamber for the mud of part-cylindrical shape having an open inlet and end walls, said chamber having an opening formed in one of said end walls and a discharge aperture formed in the other of said end walls an open ended movable cylinder of a length at least as great as that of the chamber between the end walls thereof arranged coaxially with the cylindrical part of said chamber slidably movable in said opening and axially movable for a distance substantially equal to the distance between the end walls thereof, a fixed cylinder adjacent said chamber and secured thereto, a fixed annular seating for the open end of said movable cylinder surrounding said discharge aperture, a piston axially movable within said movable cylinder, fluid pressure operated driving means to move said movable cylinder axially from a position in which the open end of the movable cylinder is adjacent one end wall of said chamber to a position in which said open end engages said seating, said driving means including a fluid inlet and outlet formed in said fixed cylinder, and additional driving means to move said piston axially within said cylinder.

4. A pump for pumping mud comprising a chamber for the mud, said chamber having a wall with a discharge aperture formed therein, an open-ended cylinder axially movable through the chamber, a fixed annular seating on said wall of the chamber for the open end of the cylinder surrounding said discharge aperture, a first piston axially movable within the cylinder, a second fixed cylinder, a second piston axially movable within said second cylinder, a rigid connection between the second piston and the movable cylinder, a third piston axially movable within said second cylinder, a rigid connection between said first and third pistons, means to supply pressure fluid alternately to opposite sides of the second piston, means to connect to exhaust the side of the second piston opposite to that connected to the supply of pressure fluid and driving means to move said third piston axially within said second cylinder and the first piston axially within the open-ended cylinder.

5. A pump for pumping mud comprising a chamber for the mud, said chamber having a wall with a discharge aperture formed therein, an open-ended cylinder axially movable through the chamber, a fixed annular seating on said wall of the chamber for the open end of the cylinder surrounding said discharge aperture, a first piston axially movable within the cylinder, a second fixed cylinder, a second piston axially movable within said second cylinder, a rigid connection between the second piston and the movable cylinder, a third piston axially movable within said second cylinder, a rigid connection between the third piston and the first piston, means to supply pressure fluid alternately to one side of the second piston, one side of the third piston, and the other side of the second piston and means to connect to exhaust alternately the other side of the second piston, the other side of the third piston and the one side of the third piston, respectively.

6. A pump for pumping mud comprising, a chamber for mud of part-cylindrical shape and

having two end walls and an open inlet, said chamber having an opening formed in one of said end walls and a discharge aperture formed in the other of said end walls, an open-ended cylinder arranged coaxially with the cylindrical part of the chamber, slidably carried in said aperture and axially movable for a distance substantially equal to the distance between the end walls of the chamber, an annular fixed seating in the other end wall of the chamber for the open end of the said cylinder surrounding said aperture, a discharge pipe for the mud connected to said aperture in the other end wall of the chamber, a first piston movable within said cylinder, a second fixed cylinder of a cross section greater than the first mentioned cylinder and secured on the outside of the chamber, coaxial with the cylindrical part thereof and surrounding said aperture in the one end wall of the chamber, a second piston axially movable in said second cylinder secured to and closing the outer end of the first

mentioned cylinder, a third piston axially movable in said second cylinder beyond the second piston, a rod member passing through an aperture in the second piston and secured at its ends to the first and third pistons, a spacer member, of a size greater than that of the aperture in the second piston, secured to the third piston on the rod member between the second and third pistons, a plate member closing the outer end of the second fixing cylinder, and connections from a supply of pressure fluid and exhausts to the second fixed cylinder for moving the second and third pistons therein successively.
